UNITED STATES PATENT OFFICE.

WILLIAM M. BIRCH, OF CRAWFORDSVILLE, INDIANA.

FENCE-TIE.

No. 893,301.

Specification of Letters Patent. Patented July 14, 1908.

Application filed November 23, 1907. Serial No. 403,555.

To all whom it may concern:

Be it known that I, WILLIAM M. BIRCH, a citizen of the United States, residing at Crawfordsville, in the county of Montgomery and State of Indiana, have invented a new and useful Fence-Tie, of which the following is a specification.

This invention relates to wire fences and has for its object to provide a strong durable fence of this character in which the line wires are positively locked in engagement with the stay wires thereby to prevent accidental displacement of the same.

A further object of the invention is to provide a fence in which the line wires are bent or wrapped around the stay wires in such a manner that when the line wires are placed under tension the loops or wraps of the latter will bite into the stay wires and thus securely clamp the parts together.

A still further object of the invention is generally to improve this class of devices so as to increase their utility, durability and efficiency as well as to reduce the cost of manufacture.

Further objects and advantages will appear in the following description, it being understood that various changes in form, proportions and minor details of construction may be resorted to within the scope of the appended claims.

In the accompanying drawings forming a part of this specification: Figure 1 is a perspective view of a portion of the fence constructed in accordance with my invention. Fig. 2 is a front elevation of one of the wire joints or ties. Fig. 3 is a top plan view of the same. Fig. 4 is a side elevation showing the loops or wraps pressed together. Fig. 5 is a top plan view of Fig. 4.

Similar numerals of reference indicate corresponding parts in all of the figures of the drawings.

The improved fence forming the subject matter of the present invention consists of a plurality of longitudinal line wires 5 fastened by staples or similar devices 6 to the fence posts 7 and spaced apart by vertical stay wires 8.

The intermediate portions of the line wires 5 are bent or coiled around the adjacent stay wire to form superposed loops or wraps 9 and

10 which bear against the front portion of the stay wire and intersect at the rear of the latter, as shown. That portion of the longitudinal wires on the opposite sides of each stay wire is extended laterally in contact with the rear walls of the loops 9 and 10, as indicated at 11 and 12 so that when the line wires are stretched or otherwise placed under tension 60 the loops 9 and 10 will bite into the stay wire and thus securely clamp the parts together.

Attention is here called to the fact that the longitudinal wires extend across and bear against the adjacent loops or wraps of each 65 tie or joint at the rear of the stay wire to form a partial closure for the eye of the loop, while the loops or wraps 9 and 10 have two points of contact with the adjacent stay wire at the front of the tie.

The tie or joint shown in Figs. 2 and 3 of the drawings is in the form of the figure 8 but if desired the loops 9 and 10 may be pressed or otherwise forced together with a suitable tool so as to produce the tie shown in Figs. 4 75 and 5 of the drawings.

While the improved tie or joint is principally designed for use in constructing wire fences it is obvious that the same may be used with equally good results in the construction of wire mats, poultry inclosures, fenders or wherever a tie of this character is found desirable.

Having thus described the invention what is claimed is:

1. A wire fence structure including intersecting line and stay wires, one of said wires being bent to form a plurality of intersecting loops engaging the other wire, the connecting wire of the loops being disposed in contact 90 with the last mentioned wire and the ends of the first mentioned wire extended across and disposed in contact with the outer walls of the loops.

2. A wire fence structure including intersecting line and stay wires, said line wire being bent around the stay wire to form superposed wraps or loops intersecting the stay wire on one side thereof, the opposite ends of the line wire being disposed in contact with 100 and extended across the adjacent loops to form partial closures for the eyes of said loops.

3. A wire fence structure including inter-

secting line and stay wires, an intermediate portion of the line wire being bent around the stay wire to form superposed wraps or loops intersecting at the rear of said stay wire, the end of the longitudinal wire forming one of the loops being extended across and having two points of contact with the wire forming the mating loop.

In testimony that I claim the foregoing as my own, I have hereto affixed my signature 10 in the presence of two witnesses.

WILLIAM M. BIRCH.
